FEEDER FOR PULVERULENT MATERIALS

Mikael Vogel-Jorgensen, Frederiksberg, near Copenhagen, Denmark, assignor to F. L. Smidth & Company, New York, N. Y., a corporation of New Jersey

Application June 21, 1938, Serial No. 214,969
In France June 22, 1937

9 Claims. (Cl. 263—32)

This invention relates to feeders for pulverulent material, such for example as cement raw material which must be fed in predetermined quantities to rotary kilns.

5 Pulverulent material tends to form lumps and cavities and thus is difficult to feed in predetermined quantities. It can be brought into a fluid-like state by being mixed with compressed air and at the same time mechanically stirred, so 10 that what may be called an emulsion of the material in air is formed.

One object of the present invention is to provide an apparatus which will feed desired quantities of such emulsified material. Another object is to measure out fixed quantities of such material at rates dependent upon those at which the material is to be used or consumed in, for example, a rotary kiln. Further objects will appear hereinafter.

20 The invention will best be understood by reference to the following description taken in conjunction with the drawings annexed hereto, which show the preferred form of apparatus according to the invention and in which:

25 Figure 1 is a diagrammatic elevation of a feeder, for supplying cement raw material to a rotary kiln through a nodulising device,

Figure 2 shows diagrammatically the feeder, the nodulising device and the rotary kiln,

30 Figure 3 is a section on the line III—III of Figure 1 and

Figures 4 and 5 show details to an enlarged scale.

The apparatus is designed to feed cement raw 35 materials in pulverulent form from a silo 1 to a rotary kiln 2 through a nodulising device 3. In such a kiln it is customary to regulate the output in accordance with the speed of rotation of the kiln and therefore it is desirable to feed the raw 40 materials to the kiln at a rate depending upon that speed. The apparatus according to the invention enables this to be done.

The apparatus includes a reservoir 4 for pulverulent material and means 5 for extracting the 45 material from the reservoir and feeding it through a hopper 6 to the nodulising device 3. The reservoir rests on an angle iron support 39. The material drops from the silo 1 into a cylindrical hopper 7 and is there brought into a fluid-like 50 state by means of compressed air supplied through a pipe line 8 and nozzles 9. The material and air in the hopper 7 are mechanically stirred by a stirrer 10 similar to the one arranged in the bottom of the reservoir 4 and as herein- 55 after described. The stirrer 10 is carried on a

shaft 11 mounted in bearings 12 carried by brackets 13 fixed to the hopper 7. The material, having thus been mixed with air, flows down through a pipe 14 to the reservoir 4. In the reservoir 4 it is further mixed with compressed 5 air supplied through a pipe line 15 branching off, like the line 8, from a common supply pipe line 16. The compressed air is supplied to the reservoir 4 through nozzles 17, and the material is there also mechanically stirred by a stirrer 18 10 carried by a shaft 19 mounted in bearings 20. The bearings are carried by brackets 21 fixed to the reservoir 4. The stirrer 18 consists, like the stirrer 10, of four rods 35 parallel to the shaft 19 and kept in correct position in relation to 15 each other by means of a number of rings 36. The rings have spokes 37 radiating from the boss 38 clamped together round the shaft 19. The shafts 11 and 19 are both driven by a motor not shown and are interconnected by a chain 22 20 which engages chain wheels 23 and 24 mounted respectively on the shafts 11 and 19.

The extracting means 5 takes the form of scoops fixed to a shaft and adapted to penetrate 25 into the reservoir below the level of the material therein and to extract therefrom at each penetration a volume of material which will be fixed so long as the level of the material in the reservoir is constant. Instead of such scoop means an 30 endless chain of paddle buckets or any other device which, assuming a constant level of material, will charge itself with a volume of material dependent only on the speed at which it works 35 may be used. In general such extracting means should move in a closed path and be adapted during each complete movement through the path, to extract a predetermined volume of material from the reservoir and to deliver that volume outside the reservoir.

The feeding device shown in the figures consists of two circular discs 25 arranged beside each other, between which two metallic bands 26 bent on a logarithmic spiral serve as scoops; their arrangement will be seen from Figs. 1 and 3. To one of the discs is fixed a boss 29 through which 45 the carrying shaft 30 is stuck. The shaft rests in the bearings 32, and the whole feeding device is kept in rotation by means of a geared motor 34 transmitting the motion through couplings 33. The shaft 30 is led in through the wall of the 50 reservoir 4 through a bushing 31 preventing the raw meal from getting out as dust at this point. From Fig. 1 appears that the feeding device for each half revolution takes up a certain quantity 55 of raw meal which it in the course of one whole

revolution carries up into the central hollow 21, whence it is led out through the spout-shaped pipe 28 into the hopper 6, to be fed to the kiln through the nodulising device. A feeding device of this description makes it possible to remove the material from the surface level in the reservoir 4 without the surface getting in motion to any extent and without the material splashing up.

10 As the material in the reservoir is in a fluid-like state, its surface level will be horizontal, but to ensure that the same amount of material is constantly removed for each revolution of the feeding device as long as it is desired it is necessary to provide means for maintaining the same surface level in the reservoir 4. For this purpose is placed in the reservoir 4 a float 40 consisting of a hollow metal box the shape of which is adapted to the shape of the reservoir. The 15 float 40 is carried by an arm 41 pivotally mounted in a bracket 42 fixed on the outside of the reservoir 4. A counterweight 43 is adjustably secured to the arm 41 so that the depth to which the float 40 immerses itself in the fluid-like material 20 can be adjusted as desired.

25 On the top face of the float is fixed a fork 73 which grips and, by means of a bolt 74, is pivotally attached to a cylindrical member 75 serving as a nut for the threaded rod 44 so that said rod 30 can be screwed more or less deep into the cylindrical member 75 as desired. The rod 44 merges at the top in a slide valve 45 which can be moved up and down in the casing 46. This slide valve 45 controls the compressed air supply from the 35 pipe line 47 so that either pipe line 48 or 49 is under pressure.

40 Fig. 4 shows details of the slide valve, and it will be seen that the slide valve in the position shown allows the compressed air to pass from pipe line 47 to 48, whereas pipe line 49, through the bore 51, communicates with the atmosphere. In case the level of material in the reservoir 4 had been higher, the buoyancy on the float would have caused the rod 44, which at the top is fitted 45 with a plate 52, to rise and overcome the pressure from the spring 53 which presses on the said plate 52 and is placed under a protecting cap 54, which further affords the requisite reaction against the spring pressure. In that case 50 there would have been open passage from the line 47—49, whereas the line 48 through bores 50 would have been in communication with the atmosphere. The slide valve is, by means of the flange 55, fixed to the overside of the reservoir 4. 55 The counterweight 43 and the spring 53, which counteract each other, damp the movement of the float 40 adequately.

60 The lines 48 and 49 lead to a compressed air motor 56 the details of which are shown in Fig. 5. This motor comprises a piston 57 which can move in the cylinder 77 and the piston rod of which carries a gate 59. This can be moved in and out of the slit 60 in the pipe 14 and thus 65 open for or cut off the supply of materials through this pipe. In order to provide tightness for the dusting raw meal the pipe is at this place surrounded by a ring 76 which is likewise fitted with a slit allowing passage for the gate 59 but which is fitted with a felt seal or the like.

70 The compressed air motor 56 is fixed to the underside of the cylindrical hopper 7 by means of a pin 62 with flange 64. The pin has a threaded journal stuck through a bore in a boss 61 on 75 the end of one cylinder cover of the compressed

air motor. A nut 78 tightens boss 61 and pin 62 together.

As the float 40 moves up and down the slide valve 45 serves to put one or other of the pipe lines 48 and 49 under pressure and thus to move 5 the piston 57 towards the right or left respectively as shown in Fig. 1. If the level of material in the reservoir becomes too high, air flows through the pipe line 49, and the gate 59 throttles the feed through the pipe 14 until the desired level 10 is again attained in the reservoir. Alterations in the desired level may be effected not only by adjusting the counterweight 43 but also by altering the position of the slide valve 45 in relation to the float 40.

15 This can be done by removing temporarily the cap 54 and the spring 53 and then by means of a suitable tool turn round the plate 52 and thereby the slide valve 45 and the rod 44 a suitable number of revolutions, whereby the rod 44 will get 20 deeper into or be lifted higher up in the threaded bore of the cylindrical member 75 so that the float 40 will be raised or lowered respectively in relation to the level of material. If any alteration according to the indicated methods is made 25 the individual quantities of material removed from the reservoir by each revolution of the feeding device 5 will also be altered.

30 From physics is known that when two vessels with confined air under pressure are put into communication with each other the air from the vessel with the highest pressure, which is assumed to be kept constant, will flow over into the other vessel until the pressure in the latter vessel is equal to the pressure in the former. So 35 long as the pressure in vessel No. 1 is considerably higher than the pressure in vessel No. 2 the air quantities flowing through in the same periods of time will be equal, and this state of affairs will continue until the pressure difference between 40 the two vessels reaches the so-called critical pressure. After that the air quantities flowing through per unit of time will be constantly decreasing. The critical pressure is reached when the pressure in vessel No. 2 is about half of that 45 in vessel No. 1.

50 Seeing that it is important for the present invention that the same air quantity is constantly supplied to vessels 4 and 7 per unit of time it must be seen that the difference between the pressures in pipes 8 and 15 (and thereby 16) and the pressure inside said vessels is above the critical pressure. As there is now inside the vessels a pressure which is slightly higher than 1 atm. it will, in pursuance of the foregoing, be understood that it is necessary that the pressure in the compressed air lines is a good 2 atms. By this arrangement is attained that the fluctuations in the quantities of air supplied are avoided. This is an important factor, because it is thereby 60 ensured that the specific weight of the mixture of air and pulverulent material remains constant, which is favourable to the measuring accuracy.

65 As previously stated, the feeding device is driven by a geared motor 34. By means of any synchronizing device of known design this motor 34 can advantageously be coupled electrically to the shaft for the motor driving the rotar kiln. Thereby is obtained that any alteration in the speed of the kiln will cause the speed of the 70 feeding device to change correspondingly. From the foregoing it will be understood that the feeding device will always take away the desired quantity of material from the reservoir for each revolution, and as it rotates at a speed which is 75

in a given proportion to the kiln speed, material is supplied to the kiln in the desired quantities.

From the hopper 6 on the feeding device the measured raw meal drops through the pipe 65 down into the hopper 66 taking the raw meal into the nodulising device 3, which on the drawings is shown in the form of a nodulising drum, fitted with live rings 67 supported on rollers 68 in bearings not shown. In the drum, which is kept in rotation by means not shown, the raw meal is transformed into nodules and it leaves the drum as such through the outlet 69, to pass down into the kiln smoke chamber 70, whence it by known devices is fed to the rotary kiln 2. 15 Only the upper end of the rotary kiln is shown with a single live ring 71 and the corresponding supporting rollers 72.

In the plant shown on the drawings the materials pass, as mentioned, from the feeding device to the rotary kiln through a nodulising device. Such a device is required for certain raw materials, but is not necessary in all cases, and it is therefore not wanted to have the invention limited to arrangements comprising such nodulising device.

I claim:

1. In an apparatus for feeding pulverulent material at desired rates, in combination, a reservoir for pulverulent material, means for emulsifying with air material in said reservoir, means moving in a closed path for extracting material from said reservoir, said extracting means being adapted during each complete movement through said path to extract a predetermined volume of material from said reservoir and to deliver said volume outside said reservoir, and means for operating said extracting means at a rate proportional to the desired rate of feed.

2. In an apparatus for feeding pulverulent material at desired rates, in combination, a reservoir for pulverulent material, means for emulsifying with air material in said reservoir, means for maintaining at a desired level the emulsified material in said reservoir, means adapted to penetrate into said reservoir below the level of material therein and to extract therefrom at each penetration a volume of material dependent upon the level of material therein and to deliver said volume outside said reservoir, and means for operating said extracting means at a rate proportional to the desired rate of feed.

3. In combination, a rotary kiln, a reservoir for pulverulent material, means for emulsifying with air material in said reservoir, means moving in a closed path for extracting material from said reservoir, said extracting means being adapted during each complete movement through said path to extract a predetermined volume of material from said reservoir and to deliver said volume to said kiln, means for rotating said kiln, and means for operating said extracting means at a rate proportional to the rate of rotation of said kiln.

4. In an apparatus for feeding pulverulent material at desired rates, in combination, a reservoir

for pulverulent material, means for supplying material to said reservoir, means for emulsifying with air material in said reservoir, float means in said reservoir actuated in accordance with the level of material therein, means operated by said float means for controlling the supply of material to said reservoir to maintain constant the level therein, means for extracting material from said reservoir in individual quantities dependent upon the level of material therein and for delivering said quantities outside said reservoir, and means for operating said extracting means at a rate proportional to the desired rate of feed.

5. In combination with the elements claimed in claim 4, a pneumatic relay operatively arranged between said float means and said supply-controlling means.

6. In combination with the elements claimed in claim 4, a counterweight connected to said float means, and means for adjusting said counterweight.

7. In an apparatus for feeding pulverulent material at desired rates, in combination, a reservoir for pulverulent material, means for supplying material to said reservoir, means for emulsifying with air said material before delivery to said reservoir, means for maintaining said material in an air-emulsified state in said reservoir, means moving in a closed path for extracting material from said reservoir, said extracting means being adapted during each complete movement through said path to extract a predetermined volume of material from said reservoir and to deliver said volume outside said reservoir, and means for operating said extracting means at a rate proportional to the desired rate of feed.

8. In an apparatus for feeding pulverulent material at desired rates, in combination, a reservoir for pulverulent material, means for emulsifying with air material in said reservoir, means for maintaining at a desired level the emulsified material in said reservoir, rotary scoop means adapted to dip into the material in said reservoir and to extract material from said reservoir and to deliver said material outside said reservoir, and means for rotating said scoop means at a rate proportional to the desired rate of feed.

9. In an apparatus for feeding pulverulent material at desired rates, in combination, a reservoir for pulverulent material, means for supplying pulverulent material to said reservoir, means for controlling the rate at which material is supplied by said supply means, means for emulsifying with air material in said reservoir, float means in said reservoir actuated in accordance with the level of material therein, relay means connecting said float means and said controlling means, scoop means adapted to dip into the material in said reservoir and to extract material therefrom and to deliver said material outside said reservoir, and means for operating said scoop means at a rate proportional to the desired rate of feed.
